CLAIM

The ornamental design for a high performance IC-engine ignition coil, as shown and described.

DESCRIPTION

FIG. 1 is a front elevational view of a high performance IC-engine ignition coil showing my new design;

FIG. 2 is a top plan view thereof;

FIG. 3 is a left side elevational view thereof;

FIG. 4 is a right side elevational view thereof;

FIG. 5 is a rear elevational view thereof;

FIG. 6 is a bottom plan view thereof; and,

FIG. 7 is a top, right perspective view thereof.

The broken line showing of the opposed mounting bracket portions and the twin electrical terminals with fastener nuts is for illustrative purposes only and forms no part of the claimed design.
